UNITED STATES PATENT OFFICE.

EDMUND P. KINNE, OF ALLIANCE, OHIO, ASSIGNOR TO AMERICAN STEEL FOUNDRIES,
OF CHICAGO, ILLINOIS, A CORPORATION OF NEW JERSEY.

COUPLER MECHANISM.

REISSUED

Application filed October 7, 1926. Serial No. 139,964.

This invention relates to coupler mechanism, and more particularly to means for operating the coupler from the side of the car.

5 In a co-pending application, Serial No. 137882, filed Sept. 27, 1926, in the name of Edmund P. Kinne, there is disclosed and claimed improved means for operating a coupler lock from locking position to lock 10 set position and to full knuckle throw position. My invention relates to the same general subject matter.

One object of the invention is to improve the operation of couplers and more particularly the standard A. R. A. coupler in a manner whereby the coupler can always be operated positively and easily to either lock set or full knuckle throw positions through the medium of the uncoupling rod.

20 Another object is to provide simple, reliable and efficient coupler operating mechanism having cooperating parts which function in an improved manner to accomplish the best results under service conditions.

25 These and other objects are accomplished by means of the arrangement disclosed on the accompanying sheets of drawings, in which—

Figure 1 is a fragmentary vertical sectional view of a standard A. R. A. bottom lift type of coupler embodying my invention, the lock being shown in locking position;

30 Figure 2 is a top plan view of the same coupler showing the operating rod and its connections to coupler parts and to the car end structure;

Figure 3 is a front elevation of the arrangement shown in Figure 2; and

40 Figure 4 is a side elevation of the arrangement shown in Figures 2 and 3.

The various novel features of the invention will be apparent from the following description and drawings and will be particularly pointed out in the appended claims.

45 Referring to the figures of the drawings, it will be noted that my invention is illustrated in connection with a standard A. R. A. type of coupler having a head 10 to 50 which a knuckle 11 is pivoted by a pin 12. As shown in Figure 1, the knuckle 11 is held in closed position by a lock 13 in which position a rear shoulder 14 of the lock rests upon the knuckle opener 15. The lock 13 has a 55 depending leg 16, the lower end of which

is provided with an inclined slot 17 adapted to slidably receive a transverse finger 18 of a lifter link 19, the other end of which has a transverse finger 20 received within the outer eye portion 21 of a lifter arm 22. 60 The inner end of the lifter arm 22 has a slot 23 for receiving a key portion 24 of a rotary member 25 supported between depending lugs 26 formed on the lower portion of the head 10 just to the rear of the 65 bottom lock hole 27.

From the arrangement thus far described, it will be appreciated that if the rotary member 25 is rotated in a clockwise direction as viewed in Figure 1, the finger 18 will 70 be moved into the upper end of slot 17 for releasing any engagement between the anti-creep members 27 and 28, whereupon the lock 13 will be raised from the locking position shown in said figure to lock set position, 75 and upon further rotation of said rotary member 25 in the same direction, said lock 13 will be moved into full knuckle throw position as fully described in said Kinne co-pending application. 80

One end of the rotary member 25 is provided with an eye portion 29 which receives a hook 30 at the inner end of an operating or uncoupling rod 31. The outer end of the operating rod is slidably supported in a guide formed between two guide lugs 32 formed at the upper inner end of a bracket 33 secured to the car end structure 34 near the outer end of the latter. The outer end of the operating rod 31 terminates in a handle 35 having an offset portion 36 to the right thereof, as shown in Figure 4, whereby there is a tendency for the operating rod 90 normally to rotate in a clockwise direction as viewed in Figure 4, and a counterclockwise direction as viewed in Figure 1, or in other words, in a direction to prevent a release of the anticreep portions 27 and 28.

The operating rod 31 is loosely mounted 95 between the guide lugs 32 for permitting centering of the coupler 10. Said operating rod 31 extends at an angle to the horizontal transverse center of the coupler and extends in a straight line inwardly forwardly and downwardly from the guide portion 32 of the bracket 33 to the eye portion 29 of the rotary member 25. In this way the operating rod is shorter and lighter than those used heretofore. Being straight 105 from the supporting bracket to the rotary 110

- member 25 eliminates the necessity of supporting the operating rod at its inner end by an additional bracket secured to the car end structure. The guide members 32 of 5 the bracket extend in the same angular direction as the operating rod 31 as does the front guide edge of the forwardly extending flange 37 of the bracket 33. The upper part of the handle 35 engages the guide 10 flange 37 and the outer part of the uncoupling rod 31 engages the guideway formed by the guide lugs 32. A retaining pin 38 extending between the guide lugs 32 locks the uncoupling rod in position.
- 15 By means of this arrangement it is a simple matter to operate the lock 13 from the side of the car by merely rotating the handle 36 of the uncoupling rod 31 in a counter-clockwise direction, as shown in Figure 4.
- 20 By means of this mechanism, the objects of the invention are accomplished.

I claim:

1. In coupler mechanism having a movable lock, the combination of a rotary member 25 for transmitting operating movements to the coupler lock, a bracket, and an operating rod supported by said bracket and

extending and connected to said rotary member for rotating the latter for operating the coupler lock, said operating rod having a handle with an offset portion tending to prevent a swinging movement of said rod which would release the coupler anticreep.

2. In combination, a coupler having a head and a lock operable therein, a rotary member for transmitting operating movements to the coupler lock, a bracket adapted to be secured to the car end structure and having an inclined guideway and an inclined guide flange, and an operating rod 35 guidedly supported in said inclined guideway portion and having a handle cooperating with said inclined guide flange, said operating rod extending from said bracket in a straight line to said rotary member for 40 rotating the latter for operating the coupler lock, said interengaging portions of the operating rod and its handle with said inclined portions facilitating centering movements of said coupler.

Signed at Alliance, Ohio, this 2nd day of October, 1926.

EDMUND P. KINNE.
